UNITED STATES PATENT OFFICE.

WALTER MORRIS LANGSDORF, OF NEW YORK, N. Y., ASSIGNOR TO S. LANGSDORF & CO., INC., OF NEW YORK, N. Y., A CORPORATION OF NEW YORK.

DESIGN FOR A VANITY CASE.

Application filed February 3, 1925. Serial No. 12,249. Term of patent 3½ years.

To all whom it may concern:

Be it known that I, WALTER MORRIS LANGSDORF, a citizen of the United States, and a resident of the city of New York, borough of Manhattan, in the county and State of New York, have invented a new, original, and ornamental Design for Vanity Cases, of which the following is a specification, reference being had to the accompanying drawing, forming part thereof.

I claim:

The ornamental design for a vanity case, as shown.

WALTER MORRIS LANGSDORF.
